UNITED STATES PATENT OFFICE.

HERBERT M. STURGIS, OF KANSAS CITY, MISSOURI, ASSIGNOR, BY DIRECT AND MESNE ASSIGNMENTS, OF ONE-HALF TO ALBERT H. BROWN AND AARON LEVINGSTON, OF KANSAS CITY, MISSOURI.

CURTAIN-FIXTURE.

SPECIFICATION forming part of Letters Patent No. 763,219, dated June 21, 1904.

Application filed July 14, 1903. Serial No. 165,499. (No model.)

To all whom it may concern:

Be it known that I, HERBERT M. STURGIS, a citizen of the United States, residing at Kansas City, State of Missouri, have invented certain new and useful Improvements in Curtain-Fixtures, of which the following is a specification containing a full, clear, and exact description, reference being had to the accompanying drawings, forming a part hereof.

10 My invention relates to curtain-fixtures; and it consists in the novel construction hereinafter described and claimed.

The object of my invention is to provide an improved curtain-fixture of the class known as "self-aligning" and which shall be constructed in such a manner as to avoid a number of the defects heretofore encountered, among which may be mentioned the accidental jumping of the grip-shoes out of the guide-grooves when 20 the operating-handles are pressed together.

A further object is to provide an improved curtain-fixture in which the curtain-rod will not be shortened, but will remain of a fixed length when the handles are pressed together.

25 My improved device is especially applicable to car-windows, but of course may be used in all other suitable locations.

In the drawings, Figure 1 is a perspective view of a car-window having my invention attached thereto. Fig. 2 is a sectional plan view showing the grip-shoes mounted in the vertical guide-grooves of the window-frame. Fig. 3 is a perspective view of one end of the curtain-rod having a set of grip-shoes attached thereto. Fig. 4 is a detail sectional plan view of one end of the curtain-rod and attached grip-shoes. Fig. 5 is a sectional elevation of the central portion of the curtain-rod.

30 The curtain 1 is hung at its upper end upon the usual spring-roller, whereby said curtain will be automatically rolled up when its lower end is released and unrolled when the lower end is moved downwardly. The lower 45 end of the curtain is attached in any suitable manner to a tubular curtain-rod 2, which has upon each of its ends a fixed grip-shoe 3, which is provided with a roughened or ser-

rated grip-surface 4, which latter is embossed or elevated beyond the adjacent surface of 50 said grip-shoe. Said fixed shoes may of course be secured in position upon the ends of the curtain-rod in any desired manner, as by the use of solder or by means of screw-threads. Said fixed grip-shoes are provided 55 with perforated ears 5, between which is pivoted a movable grip-shoe 6, which latter is also provided with perforated ears 7, and these are connected to the ears 5 by means of a pivot rod or pin 8, or the same result may of course be obtained by securing them in any known manner. It will be observed that the said movable grip-shoe also has an elevated and serrated grip-surface 4 and that this grip-surface is directly opposite the grip-surface of the adjacent fixed grip-shoe. This construction is best shown in Fig. 3. The pairs of grip-shoes thus constructed at each end of the curtain-rod are mounted to slide in vertical guide-grooves 9, formed in the window-frame 10, so 60 that said grip-shoes will be moved laterally against the opposite sides of said grooves during the operation of holding the curtain. It will also be seen that the length of the curtain-rod 2 is fixed at all times and is determined and fixed by the manufacturer, and by 70 reason of the fact that the length of the curtain-rod is fixed it will be impossible for the shoes to accidentally jump out of the grooves at any time, and the only way in which they 75 can be removed from said grooves is by detaching the window stops or strips 11.

The movable jaws 6 are forced outwardly in a lateral direction by means of the rounded or wedge-shaped ends 12 of the grip-rods 85 13, which are mounted within the curtain-rod 2, with their inner ends separated a distance near the center of the length of said curtain-rod. The inner ends of the said curtain-rods are provided with the usual handles 14, which 90 are normally urged apart by means of the spring 15, mounted within said curtain-rod with its ends engaging the adjacent ends of said grip-rods. 16 indicates washers mounted upon the grip-rods within said curtain-rod 95 at suitable points for the purpose of center-

ing said grip-rods within said curtain-rod. The rounded or wedge-shaped outer ends 12 of said grip-rods are normally urged into contact with an inclined surface or projection 17, 5 formed on the inner surface of the movable grip-shoes.

The operation is as follows: When it is desired to raise or lower the curtain, the operator grasps the handles 14 and presses them toward each other, thereby causing the grip-rods 13 to approach each other and also compressing the spring 15. This movement with- 10 draws the rounded ends 12 of said grip-rods from contact with their respective inclined surfaces 17 on the inner face of the movable grip-shoes 6, and such movement of said grip-rods releases all the grip-shoes and permits the curtain to be moved in the desired direction. When the operator releases the han- 15 dles 14, the spring 15 causes the grip-rods 13 to resume their normal position, thereby forcing the rounded ends 12 into contact with the inclined surfaces 17 of the said movable grip-shoes, which movement will cause the said 20 movable shoes to be moved laterally within the guide-grooves 9 and cause the roughened or serrated surface 4 to securely grip the walls of said grooves. After said movable grip-shoes have been forced into contact with 25 the walls of the grooves the rounded ends of said grip-rods will continue to move until they are forced into contact with the fixed grip-shoes 3, and the latter will also be moved in a direction opposite that of the movable 30 grip-shoes, and in this way both grip-shoes of each set will be forced into contact with the walls of the said grooves, and the curtain will be very securely retained at the desired 35 point of adjustment.

40 It will be observed that the curtain-rod 2 is not shortened or lengthened during the operation above described, and consequently it will be impossible for the grip-shoes to ever jump out of the guide-grooves.

45 What I claim is—

1. The improved curtain-fixture, comprising a curtain, means for suspending the upper

end of said curtain, a curtain-rod at the lower portion of said curtain, fixed grip-shoes at the outer ends of said curtain-rod by means of 50 which the length of said rod is fixed and unalterable, movable grip-shoes pivotally connected to said fixed grip-shoes, and a wedging device constructed to be projected between pairs of said grip-shoes to force them apart 55 and cause same to grip the opposite walls of the guide-grooves in which said grip-shoes are adapted to be located during use, substantially as specified.

2. The improved curtain-fixture, comprising a curtain, means for suspending the upper end of said curtain, a curtain-rod at the lower portion of said curtain, fixed grip-shoes at the outer ends of said curtain-rod by means of 60 which the length of said rod is fixed and unalterable, movable grip-shoes pivotally connected to said fixed grip-shoes, a wedging device constructed to be projected between pairs of said grip-shoes to force them apart and cause them to grip the opposite walls of the 65 guide-grooves in which said grip-shoes are adapted to be located during use, and suitable handles for controlling the wedging device at each end of said curtain-rod, substantially as specified.

3. In a curtain-fixture, a curtain, a curtain-rod secured to said curtain, fixed shoes at the outer ends of said curtain-rod, movable shoes hinged to said fixed shoes, said shoes having raised serrated grip-surfaces, wedging devices 80 mounted between pairs of said grip-shoes and extending to a point near the center of the length of said curtain-rod, a spring for retaining said wedging devices in normal position, and handles connected to said wedging devices, 85 substantially as specified.

In testimony whereof I have signed my name to this specification in presence of two subscribing witnesses.

HERBERT M. STURGIS.
